DESIGN FOR A BATHTUB

Rufus L. Yent, Pittsburg, Calif.

Application January 12, 1933. Serial No. 46,800

Term of patent 14 years

To all whom it may concern:

Be it known that I, RUFUS L. YENT, a citizen of the United States, residing at Pittsburg, in the county of Contra Costa and State of California, have invented a new, original, and ornamental Design for a Bathtub, of which the following is a specification, reference being had to the accompanying drawing, forming part thereof.

I claim:

The ornamental design for a bathtub as shown and described.

RUFUS L. YENT.
